HANDLE-MOUNTED FLOOR WAXER HAVING
LIQUID DISPENSER WITH VALVE OPER-
ABLE FROM UPPER END OF HANDLE

Chester R. Pollitt, Portland, Oreg.

Application November 18, 1946, Serial No. 710,554

3 Claims. (Cl. 222—162)

1

This invention relates to a liquid dispenser, particularly adapted for applying a liquid cleaner or wax to hardwood floors.

The prime object of the invention is to combine or associate a liquid container with a pad or brush, mounted on a handle, with means to control the dispensing of liquid from the container to the rear of a brush or the like.

A further object of the invention is to provide a liquid dispensing container in the form of a standard jar, as for instance, a fruit jar, with suitable valve mechanism operable by controls on a handle to control the discharge of liquid.

A still further object of the invention is to provide means for dispensing liquid to a floor adjacent a pad or brush, so that the pad or brush can uniformly spread the liquid when the dispenser is reciprocated.

Another object of the invention is to provide valve means for controlling the dispensing of liquid adjacent a brush or pad to spread same over a floor.

A further object of the invention is to provide in a liquid dispenser, a liquid container slideable in a frame or cradle to open or close liquid exit openings controlled by a valve.

In the accompanying drawings:

Figure 1 is a plan view of the liquid dispensing device, parts being broken away for convenience of illustration, the position of the liquid container being indicated by broken lines.

Figure 2 is a side view of Figure 1, illustrating the liquid container in position.

Figure 3 is an enlarged fragmentary sectional view of the device illustrating the valve within the liquid container in closed position and taken on line A—B of Figure 1.

Figure 4 is a sectional view of the device taken on line A—B of Figure 1 illustrating the valve in open position.

Figure 5 is an underneath perspective view of the device with the pad or brush removed.

The liquid dispenser consists of a frame 1, including a rearwardly and upwardly inclined cradle and a flat forwardly extending horizontal flange 2. To the flange 2 is attached a suitable pad or brush 3, the same being secured in position by a bolt 4, passing through an opening 5 formed in the flange 2, and held in position by a nut 6.

In the lower end of the cradle is formed a transverse trough 7 formed in its bottom with a series of exit openings 8 for spreading liquid to the floor surface 9, the liquid being delivered to the trough from a container 10 supported in the cra-

2

die. The container 10 may consist of an ordinary fruit jar or the like, having a lid 11 screwed thereon.

The flat portion 13 of the lid 11 is formed with a hub 15, and a threaded annular flange 12 to engage the threaded end of the container.

A stem 14 extends through the hub 15, and a flexible gasket 16 is interposed between the lid and the mouth 17 of the container 10 to form a seal. The gasket 16 and the lid 11 are formed with exit openings 18, controlled by a valve 19, adjustably mounted on the upper end of the stem 14 by adjusting screws 20, which are threaded through a cross bar 21, secured to the inner end of the stem as shown at 22. The ends of the adjusting screws 20 are rotatably mounted in a flange 23, forming part of the valve 19. The screws 20 provide means for adjusting the valve toward and from the lid to regulate the amount of liquid delivered through the exit openings 18, as shown at 24.

The lower end of the stem 14 is provided with a head 25 which seats against a flange 26 extending forwardly and upwardly from the lower end 23 of the cradle. A spring 27 surrounds the stem 14, and at one end bears against the head 25, and its opposite end surrounds the hub 15 and bears against the flat part 13 of the lid 11. The spring holds the head of the stem against the flange 26 and forces the container upwardly in the cradle and the lid up against the valve 19 to close the openings 18, as shown in Fig. 3.

The container 10 is supported in the cradle, and spring clips 28, are employed to retain it in position, as best shown in Fig. 2. 29 indicates a hollow handle fitted in a socket 32, from which extends two rods 31 which pass through sleeves 30 on the sides of the cradle. The lower ends of the rods are bent horizontally and pass through openings 33 in the flange 26, and are secured to the flat forwardly extending horizontal flange 2, as shown at 33.

A plunger rod 34 extends through the handle. The rod is provided at its lower end with a head 35 which engages the upper closed end of the container 10, as shown at 36. The upper end of the plunger rod 34 has a knob 37 for the operator to press the plunger rod down against the container. When the plunger rod 34 is depressed, it slides the container in the cradle against the tension of the spring 27, and forces the lid 11 away from the valve 19, which allows liquid to pass through the exit openings 18 to the trough 7, as shown in Fig. 4. Thus the liquid is free to flow through the exit openings 18 to the

trough and from there distributed through the exit openings 8 to the floor in rear of the pad or brush.

Upon release of pressure on the knob 31, the spring 27 will act to return the container and plunger rod to normal position. Thus the lid 11 is brought into contact with the valve 19 and the exit openings 18 are closed.

What I claim is:

1. A liquid dispenser, comprising a frame curved in cross section to form a cradle provided at its lower end with a transverse trough having exit openings in its bottom, a liquid container having exit openings formed in one of its ends and slidably mounted in the cradle, a flange extending upwardly and forwardly from the lower end of the cradle, a valve on the inside of the container to control the exit openings in the end of said container, a stem extending through the end of the container and the valve, the lower end of the stem having a head which engages the forwardly and upwardly extending flange, a cross bar secured to the upper end of the stem, screws threaded in the cross bar with their inner ends rotatably mounted on the valve, a spring between the lower end of the container and the head on the stem to normally urge the container upwardly in the cradle to close the valve, a handle extending from the cradle, and means on the handle engaging the upper end of the container for sliding said container downwardly in the cradle against the tension of the spring to open the valve for release of liquid through the exit openings in the end of the container to the transverse trough.

2. A liquid dispenser comprising a frame including a flat forwardly extending horizontal flange and a cradle extending upwardly and rearwardly from the flat horizontal flange, a transverse liquid receiving trough formed at the bottom of the cradle adjacent the flat forwardly extending horizontal flange, the bottom of the trough having formed therein a series of exit openings, a flange extending forwardly and upwardly between the lower end of the cradle and the flat forwardly extending horizontal flange, a slidably mounted liquid container supported in the cradle with the lower end extended over the transverse trough, the lower end of the container having a series of exit openings formed therein, a valve located on the inside of the lower end of the container for controlling the exit openings in the lower end of the container, a stem having a head engaging the upwardly and forwardly extending flange, the stem extending through the

lower end of the container, and into the lower end of said container, a spring surrounding the stem and interposed between the head and the lower end of the container, means mounted on the inner end of the stem for regulating the position of the valve with reference to the exit openings in the lower end of the container, a handle extending from the cradle, and means carried by the handle engaging the upper end of the liquid container for sliding the container downwardly in the cradle against the tension of the spring to open the valve for release of liquid through the exit openings in the lower end of the container to the trough.

- 10 5. A liquid dispenser, comprising a supporting frame, including a rearwardly and upwardly extending cradle and a flat forwardly extending horizontal flange and an upstanding flange projecting upwardly from the flat forwardly extending flange, a transverse trough formed in the bottom of the cradle adjacent the flat forwardly extending horizontal flange, a series of exit openings formed in the bottom of the transverse trough, a liquid container slidably mounted in the cradle with its lower end extending over the transverse trough, the lower end of the container having formed therein a series of exit openings, valve mechanism at the lower end of the liquid container including a spring pressed normally closed valve engaging the inner surface of the lower end of the container and a stem projecting from the valve with its free end in engagement with the upstanding flange for controlling discharge of liquid from the exit openings in the lower end of the container, a handle secured to the cradle, and means on the handle engaging the upper end of the container to slide liquid container in the cradle to free the exit openings in the lower end of the container to permit discharge of liquid through the exit openings in the lower end of the container to the transverse trough.
